United States Patent Office

Des. 182,043
Patented Feb. 4, 1958

182,043

VEHICLE WINDSHIELD

Alfred B. Sanchez, Sandia, Tex.

Application July 15, 1957, Serial No. 46,932

Term of patent 7 years

(Cl. D14—6)

Fig. 1

Fig. 2

The portions of a vehicle shown in broken lines are for purposes of illustration only.

I claim:

The ornamental design for a vehicle windshield, substantially as shown and described.
